United States Patent

Des. 241,458
Patented Sept. 14, 1976

241,458

GAME BOARD

Robert Harold Hudson, Seekonk, Mass., and Robert Lucien Carignan, Providence, R.I., assignors to Hasbro Development Corp.

Filed June 2, 1975, Ser. No. 582,992

Term of patent 14 years

Int. Cl. D21—01

U.S. Cl. D34—5 SS

FIG. 1

FIG. 2

FIG. 3

FIG. 4

FIG. 1 is a top plan view of a game board showing our new design;

FIG. 2 is a front elevational view thereof;

FIG. 3 is a bottom plan view thereof; and

FIG. 4 is a rear or side elevational view, the board having the same appearance from both sides and the rear. We claim:

The ornamental design for a game board, substantially as shown and described.
